UNITED STATES PATENT OFFICE.

GEORGE D. WHITCOMB, OF CHICAGO, ILLINOIS.

COAL-MINING MACHINE.

SPECIFICATION forming part of Letters Patent No. 280,544, dated July 3, 1883.

Application filed November 10, 1882. (No model.)

To all whom it may concern:

Be it known that I, GEORGE D. WHITCOMB, a citizen of the United States, residing at Chicago, in the county of Cook and State of Illinois, have invented certain new and useful Improvements in Coal-Mining Machines, which are fully set forth in the following specification, reference being had to the accompanying drawings, in which—

- 10 Figure 1 represents a longitudinal vertical section of a coal-mining machine embodying my improvements; Fig. 2, a detail of the upper portion of Fig. 1, on an enlarged scale; Fig. 3, a detail plan of the valve-chest on a scale enlarged from that of Fig. 2; Fig. 4, a detail section taken on the line *x x*, Fig. 3, on same scale; Fig. 5, a similar section taken on the line *y y*, Fig. 3, on same scale; Fig. 6, a detail elevation of the front cylinder-head on same scale; Fig. 7, a detail section taken on the line *z z*, Fig. 6, on same scale; Fig. 8, an elevation of the packing-ring detached, shown in Fig. 7.

25 My present invention relates to coal-mining machines similar to that shown in Letters Patent No. 232,792, issued to me September 28, 1880, and in an application for patent heretofore filed by me, June 12, 1882; and allowed October 5; and it consists in certain improvements upon the machines shown and described 30 in said patent and application.

35 I will proceed to describe in detail the construction and application of my present improvements, referring to such portions of the machines heretofore shown and described by me as may be necessary for this purpose.

40 My present improvements are for the purpose of perfecting the machines in such parts as have been found desirable by actual use. The blow struck by the engine is very heavy, and a great strain is brought upon the pick and other parts of the machine. The effective work of the machine is also dependent upon 45 tightness of the joints about the piston. If there is leakage, especially at the front end of the piston, the operation is greatly impaired. I have also found difficulty in regulating the supply of compressed air to the valve-engine. The quantity of air required to drive this engine is comparatively small, and the regulation is therefore comparatively fine. Expe-

rience has proved that in operating an air-compressor at or near a coal mine a large amount of dust is taken in with the air and becomes mixed with the condensed water in the pipes. 55 It is also found that the oil used for lubricating machinery run by compressed air is liable to congeal. Consequently in regulating entirely by the inlet-port the port is necessarily made so small as to cause trouble by its becoming clogged by the dust and congealed oil. To avoid this difficulty I at first attempted to regulate at the exhaust-port, but experienced difficulty from back-pressure. I have therefore adopted a twofold regulation at both inlet 60 and outlet. I also have found it an improvement to place the regulating stop-valve of the inlet in the port between the gate and eccentric of the rotary engine, rather than (as shown in my Patent No. 232,792) in the port between 65 the gate and the main valve-chamber, since a stop-valve in the latter situation impairs the pressure requisite to hold the gate to the eccentric. My present improvements are intended to obviate these several difficulties, and 70 thereby improve the efficiency of the machine for practical use.

75 The main features of the machine are like those of the similar machine shown in my patent and application mentioned above, and do not require description here.

In the drawings, A represents the cylindrical chamber, in which the cylinder or piston B of the rotary engine that operates the valve is arranged to revolve. These parts are of 85 ordinary construction, and the engine is provided with the usual gates or valve, C, arranged upright in the frame-work, and resting on its lower edge upon the eccentric hub or piston.

The supply of compressed air is let into a 90 chamber, D, as in my prior machines, from which leads an air-passage, E, extending up and opening in over the gate, which at its lower end is cut away on the side next to the passage part way across, as seen in Fig. 2 of 95 the drawings. The air therefore is admitted over the gate, and holds the latter down upon the rotary piston, which, as usual, is mounted eccentrically in its chamber.

The inlet-port F of the engine is arranged, 100 as usual, on one side of the gate, between which and the upright is the partition G, in the up-

per portion of which is an aperture, *g*, opening from the gate-space into the inlet, so that as the gate drops in following the surface of the piston, and passes below the aperture *g*, 5 air will be admitted to the inlet and pass directly to the piston, as usual.

A cap, *a*, is arranged over the machine, covering all the openings mentioned, and in this cap is arranged a screw stop-valve, *b*, 10 which passes down through the cap and enters the upper end of the inlet-port, as shown in Fig. 5 of the drawings. The cap is provided with a suitable stuffing-box, through which this stop-valve passes down into the inlet-port 15 far enough to entirely close the opening *g* in the partition, if desired, and consequently affords a means for regulating with nicety the size of this opening, thereby governing the admission of air to the inlet-port. At the 20 same time the pressure of air on the gate, whereby it is held down to the eccentric *B*, is not diminished. I am enabled to secure this result easily by arranging the inlet-port as described above and extending it up through 25 the chest under the cap. The outlet-port or exhaust-port *H* also extends upward and outward from the chamber on the other side of the gate, and near its end finds an outlet 30 through a side passage, *h*, the upper end of the port being closed with a screw-plug, *h'*. A screw stop-valve, *H'*, is inserted from the other side of the chest into the exhaust-port, so as to close the side opening, *h*, at pleasure, and hence also to regulate the opening through 35 which the air escapes into this side passage, thereby regulating the exhaust in a similar way as the supply is regulated. This stop-valve passes through a suitable stuffing-box inserted in the side of the chest.

40 It is obvious from the construction described above that both the supply and exhaust of the valve-engine may be nicely regulated, so as to work in unison, thereby keeping the air-pressure upon the top of the gate substantially uniform, and also enabling me to regulate the supply of air to the engine with great nicety. The main cylinder *I* and piston *I'* are substantially the same as in my application mentioned above, and are constructed to obtain 45 the cushioning effect therein set forth. At the front end of the cylinder there is also a packing, *i*, for the piston-rod, as in the case mentioned. I have found, however, that under the great shock occasioned by the stroke 50 there is great danger of leakage of air, and when this occurs the cushioning effect is lost. I have therefore provided an additional security against this leakage by also putting a packing in the cylinder-head *J*, and constructed 55 in a peculiar manner. The inner end of this cylinder-head is recessed, the recess being stepped, as at *j'j''*. (Shown in Fig. 7 of the drawings.) I provide a packing, *K*, which is adapted to fit the smaller portion of the re-

cess, and is made in the form shown in Fig. 65 7, being composed of an annular portion, *k*, and an outwardly-projecting flange, *k'*, which is adapted to rest on the seat *j*. The outside of the annular portion is beveled, and over this packing is fitted a suitable packing-ring, 70 *L*, which is angular in cross-section, one portion, *l*, resting upon the flange of the packing, and the other outwardly-projecting portion, *l'*, resting on the step *j'*. This ring holds the packing in place, and when these parts 75 are in position, as shown in Fig. 7 of the drawings, there will be a small tapering space between the packing and the ring, opening inward toward the cylinder. The head is fitted upon a flange, *i'*, on the outside of the cylinder, which fits against the step *j''*, as in the machine shown in my prior application.

80 I have found this improvement of very great utility. If, from any cause, there should be a slight leakage from the cylinder around the piston, or the packing thereof in the end of the cylinder, it will find its way to the packing in the cylinder-head, where it will only tend to tighten the latter on the piston by entering the space between the packing and the 85 packing-ring and pressing the former more closely upon the piston. The amount of air escaping in any event would be slight; but this slight amount is sufficient to impair the operation described in my prior application.

85 The improvement in the packing described above will prevent even this slight leakage.

90 Some modifications may be made in the construction and arrangement of the devices mentioned above without departing from the leading features of my improvements.

95 Having thus described my invention, what I claim as new, and desire to secure by Letters Patent, is—

100 1. The gate *C*, in combination with the inlet-port *F*, extending upward through the chest, the partition *G*, provided with the aperture *g*, and the stop-valve *b*, arranged in the inlet-port to regulate the supply of air, substantially as described.

105 2. The gate *C* of the valve-engine, in combination with the inlet-port *F*, the partition *G*, provided with aperture *g*, regulating-valve *b*, exhaust-port *H*, and regulating-valve *H'*, substantially as and for the purposes set forth.

110 3. The cylinder *I*, in combination with the piston *I'*, the packing *i*, the cylinder-head *J*, and the beveled packing *K*, substantially as and for the purposes set forth.

115 4. The cylinder *I*, provided with packing *i*, in combination with the cylinder-head *J*, beveled packing *K*, and packing-ring *L*, substantially as and for the purposes set forth.

120 GEO. D. WHITCOMB.
